UNITED STATES PATENT OFFICE.

JULIUS LOEB STRAUSS, OF NEW YORK, N. Y., ASSIGNOR TO ROSE STRAUSS CO., OF NEW YORK, N. Y., A COPARTNERSHIP COMPOSED OF CHARLES M. ROSE AND JULIUS L. STRAUSS.

PORTABLE ELECTRIC LAMP.

1,171,274.

Specification of Letters Patent.

Patented Feb. 8, 1916.

Application filed January 6, 1915. Serial No. 735.

To all whom it may concern:

Be it known that I, JULIUS L. STRAUSS, a citizen of the United States, and a resident of the city of New York, borough of Manhattan, in the county and State of New York, have invented a new and Improved Portable Electric Lamp, of which the following is a full, clear, and exact description.

Among the principal objects which the 10 present invention has in view are: to provide a movable electric lamp having a flexible connecting wire, with means for automatically and at will gathering a portion of said wire; to provide a gathering mechanism for 15 electric lamp cord, said mechanism being adapted to wrap said cord in a coil of small compass; to provide a portable lamp having a hinged standard rotatable to vary the plane of the swing of said standard; to provide a 20 rotatable lamp-supporting standard and a non-rotatable supporting base therefor; and to provide electric-circuit connections disposed in said base to permit independent movement of the lamp-supporting standard 25 above referred to.

Drawings.—Figure 1 is a side view of a lamp constructed and arranged in accordance with the present invention, the broken lines shown therein being used to illustrate 30 some of the various positions to which said lamp may be moved in service; Fig. 2 is a vertical section through the base shown in Fig. 1, the lamp standard being in part broken away; Fig. 3 is a cross section taken 35 on the line 3—3 in Fig. 2; Fig. 4 is a detail view in vertical cross section of a cord-winding reel taken as on the line 4—4 in Fig. 5; Fig. 5 is a horizontal section taken as on the line 5—5 in Fig. 2; Fig. 6 is a horizontal 40 section taken as on the line 6—6 in Fig. 2; Fig. 7 is a horizontal section taken as on the line 7—7 in Fig. 2; Fig. 8 is a view of the bottom of the lamp base, the view being taken as from the position indicated by the 45 numeral 8 in Fig. 1 of the drawings. Fig. 9 is a side view of a lamp base having spring slide plates and arms for supporting the base on a standing structure.

Description.—As seen in the drawings, the

electric-light globe 15 is mounted in a socket 16. The socket 16 is provided with a switch embodying an operating button 17. The socket 16 is mounted on the end of a short standard 18, the lower end whereof is pivotally mounted by means of a pin 19 between 5 the sides of a yoke 20. In Fig. 1 of the drawings several positions are illustrated to which the lamp may be moved. When the lamp has been properly positioned with reference to the base and the short standard 21 thereof, a clamping nut 22 is manipulated to bind the knuckle 23 on the standard 18 in the yoke 20. Mounted upon the globe 15 is a shade 24. The shade 24 is held in service relation to the globe 15 by hollow-centered 6 gripping loops 25. The formation of the loops 25 and the grip of the same on the globe 15 are such that the shade may be moved around said globe, or pivoted to swing about the same as on a pivot member. 7

In certain service positions of the base 26 said base remains in the position in which it is set. As seen best in Fig. 8 of the drawings, I provide arms 27, disposed each at one end of the slide plates 28. The slide plates 28 are slidably mounted in a groove formed in the base 26, and are both provided with elongated slots which infold a screw-threaded pin 29. The pin 29, in conjunction with a slot 30 formed in the base 26, constitutes a satisfactory guide controlling the movement of the plates 28. As shown by the dotted lines in Fig. 8, the plates 28 are extended to permit the arms 27 to be passed behind a shelf or rail 61, as seen best in Fig. 9 of the drawings. Said rail, it will be understood, forms part of a standing structure. When the plates 28 are satisfactorily adjusted, a screw-nut 31 is set up on the pin 29 to force the plate 32' upon the lapped portions of said plates 28, to hold the same definitely in the adjusted position.

To hang the lamp on the side wall of a standing structure there is provided a sliding eyelet plate 32. The plate 32 is mounted in a groove 33, and is provided adjacent the outer end with an eyelet 34. The plate 32 is held in the groove 33 by a screw 35.

which screw passes through an elongated slot 36 in said plate 32.

The standard 21 is constructed of tubing, and at the lower end is pivotally seated in a recess provided in the base 26. The standard 21 is held firmly in position by a machine screw 37. The upper end of the standard 21 is furnished with a stop member 38, which rests firmly upon the top of a thin metal canopy 39. The interior of the canopy 39 forms a hollow chamber, wherein operates a winding reel for the lamp-cord 40 and for a contact plate 41. The contact plate 41 is constructed from suitable insulating material, such as hard rubber or fiber, and is provided with a hub 42. The hub 42 is fitted tightly on the standard 21, and is secured to the plate 41 by means of screws 43. The plate 41 is rotated with the standard 21 and, as seen best in Fig. 3 of the drawings, is provided with electric contact rings 44 and 45. The rings 44 and 45 are suitably and electrically connected with the wires forming the local branch lamp circuit main 46, as shown best in Fig. 2 of the drawings. The main 46 is passed through an opening in the side of the standard 21, and is extended upward therethrough to be wrapped on the pin 19, from whence it is led through the standard 18 to the terminals of the switch contained in the socket 16.

From the foregoing it is obvious that the lamp embodying the standards 18 and 21 may be revolved without disturbing the main 46, and, as hereinafter set forth, may remain stationary while the winding reel is operated to gather the lamp-cord 40.

The reel for gathering the lamp-cord 40 embodies an insulating table 47. The table 47 is separated from the ratchet-toothed plate 48 by means of a hub 49. The hub 49 is tubular in form and has a reduced end 50, the lower edge thereof rests on the upper surface of the base 26 to support the reel in service. The table 47 and plate 48 are structurally united by screw-bolts 51, as best seen in Fig. 4 of the drawings. The reel so formed is operated by a coil spring 52, which spring rests beneath the plate 48 upon the base 26. Current is conveyed from the two strands of the cord 40 to the rings 44 and 45 on the plate 41 by means of spring wiper contacts 53 and 54. The contacts 53 and 54 are held in position on the table 47 by bolts 55. The under surface of the table 47 is suitably recessed to receive in countersunk relation the bolts 55 and the split strands of the cord 40.

From the foregoing it is obvious that when in service, the lamp may be placed in any suitable position, and the cord 40 may be extended to accommodate the movement of said lamp. It is also evident that the spring 52 will normally maintain the

pull on the cord 40, to wind the same on the hub 49. It will also be noted that, irrespective of the position of the base 26 and canopy 39, the standard 21 and parts connected therewith, including the lamp 15, rotate freely without disturbing said base or the cord 40 connected therewith and leading therefrom.

It is to hold the reel in position to provide sufficient slack in the cord 40, that I provide the plate 48 with ratchet teeth, such as 56, and a spring-actuated pawl 57 to engage the same. The pawl 57, as seen best in Fig. 7 of the drawings, is pivoted to the pin 58 and has a tail extension 59 provided with a button that protrudes from the side of the canopy 39. The pawl 57 is actuated by a flat spring 60 to normally engage the teeth 56 as the same pass under the latch head. When it is desired to release the plate 48 and reel connected therewith to permit the spring 52 to take in any slack which exists in the cord 40, the operator by pressing upon the button connected with the extension 59, disengages the latch 57 from said plate.

Claims:

1. A lamp as characterized, comprising a rotary standard, said standard having a plurality of pivotally-connected sections; a supporting base for said standard; a reel pivotally mounted in said base and embodying electric contacts; an electric circuit embodying a lamp-cord operatively attached to said contacts to be wound on said reel, said cord extending beyond said base; a lamp socket mounted on said standard; electric contacts connected with said standard to be rotated therewith, said contacts operatively and continuously engaging the contacts on said reel; and means connecting said socket and the contacts connected with said standard.

2. A lamp as characterized, comprising a rotary standard, said standard having a plurality of pivotally-connected sections; a supporting base for said standard; a reel pivotally mounted in said base and embodying electric contacts; an electric circuit embodying a lamp-cord operatively attached to said contacts to be wound on said reel, said cord extending beyond said base; a lamp socket mounted on said standard; electric contacts connected with said standard to be rotated therewith, said contacts operatively and continuously engaging the contacts on said reel; and a local circuit embodying wires connecting said socket and the contacts on said standard, said wires being housed in said standard and wrapped about the pivots uniting the sections of said standard.

3. A lamp as characterized, comprising a freely rotatable standard embodying an elec-

tric lamp socket; a stationary base for pivotally supporting said standard; an electric-supply circuit having stationary terminals in said base; and a local circuit in said standard embodying the lamp socket thereof and terminals movably engaging said first-mentioned terminals.

Copies of this patent may be obtained for five cents each, by addressing the "Commissioner of Patents.
Washington, D. C."

In testimony whereof I have signed my name to this specification in the presence of two subscribing witnesses.

JULIUS LOEB STRAUSS.
